UNITED STATES PATENT OFFICE

160,950

RANGE

Ralph E. Kruck, Clinton, Conn., assignor to Florence Stove Company, Gardner, Mass., a corporation of Massachusetts

Application May 5, 1949, Serial No. 2,442

Term of patent 7 years

(Cl. D81—4)

To all whom it may concern:

Be it known that I, Ralph E. Kruck, a citizen of the United States, residing at Clinton, in the county of Middlesex, State of Connecticut, have invented a new, original, and ornamental Design for a Range, of which the following is the specification, reference being made to the accompanying drawing, forming part thereof.

The figure is a perspective view of a range showing my new design. The right-hand end of the range is plain.

The characteristic feature of the range disclosed resides in the configuration of the back guard as shown.

I claim:

The ornamental design for a range, as shown and described.

RALPH E. KRUCK.
